INVENTOR

BY Victor J. Evans

WITNESS

John Donoran

ATTORNEY

UNITED STATES PATENT OFFICE.

ROBERT TOENNIGES, OF STAUNTON, ILLINOIS.

KEY.

Application filed January 25, 1926. Serial No. 33,630.

This invention relates to improvements in keys, the general object of the invention being to provide the key with a detachable portion which remains in the lock, when the bolt of the same is projected, and thus prevents insertion of other keys, so that the lock cannot be opened by an ordinary key or skeleton key.

Another object of the invention is to so make the key parts that they cannot be separated until the parts have been adjusted to project the bolt, so that the detachable portion is either fastened to the other portion or to the lock.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the improved key.

Figure 2 is a view of the detachable part, with the two portions thereof turned into locking position.

Figure 3 is a view of the handle part.

Figure 4 is an end view of Figure 2.

Figure 5 is a section on line 5—5 of Figure 4.

Figure 6 is a section on line 6—6 of Figure 5.

Figure 7 is a fragmentary view of the handle part.

As shown in these views, the key comprises the handle part 1, the lock engaging part 2 and the central part 3. The part 3 is of tubular construction and rotatably receives a tubular extension 4 on part 2 which is held in place by the screw 5 which passes through a hole formed in the wing or lug 3' of said part 3. The part 4 is provided with a slot to receive the end of the screw 5 and this slot is so formed that the parts 2 and 3 can be moved a quarter turn relative to each other. The part 2 is provided with a wing or lug 2' which is shaped to fit the narrow part of the keyhole of the lock to which the key belongs, and this part 2 is provided with a bore 6 and a collar 7, the collar acting as a stop for preventing the

said part being pushed too far into the lock. This collar is formed with the notches 8 and the part 3 is provided with similar notches 9. A number of strips 10 are movably mounted in the bore 6 and are normally held in their projected position by the spring 11 which is arranged in the bore 6. Each strip is provided with a wing 12, these wings being oppositely arranged on the two strips shown in the drawings. The wings engage the notches 8 in the member 2 but when the member 3 is turned to position its wing at right angles to the wing of member 2, the notches 9 in said member 3 will be in alignment with those in member 2, so that the spring 6 will project the strips 10, and thus cause the wings 12 to engage the notches 9, which are shallower than the notches 8, so that the wings will engage both sets of notches and thus lock the parts 2 and 3 together. The outer end of the part 3 is formed with a keyhole 13 for receiving the ward 14 on the part 1, this ward being shaped to first engage one strip and push it inwardly and then the other strip to push it inwardly. When both strips are pushed inwardly, they will free the member 3 so that by rotating the part 1, the part 2 will be turned to project or retract the bolt of the lock in which said part 2 is placed; the part 3 being held stationary by the fingers of one hand, or, preferably, by having the extension of its wing 3' inserted in a portion of the keyhole of the lock. The parts 1 and 3 are so formed that when the part 1 is turned to turn the part 2 to project the bolt of the lock in which said part 2 is placed, the ward 15 can be pulled from the part 3, but when the parts are in unlock-
ing position, the ward cannot be withdrawn from the part 3, so that the entire key assembly is locked together.

From the foregoing, it will be seen that I have provided means for practically plugging up a keyhole when the bolt of the lock is in projected position, so that an ordinary key or a skeleton key cannot be used in an attempt to retract the bolt, as the part 1 is very much smaller than a key which would fit the lock. The part 1 is so small that it can be carried in the pocket without difficulty and when the parts are in unlock-
ing position, they are locked together so that there is no danger of misplacing the parts. By providing different numbers of the strips 10 and making them of various shapes, the

keys can be made to differ one from another, so that part 1 of one key cannot be used for adjusting the parts 2 and 3 of another key.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A key comprising a handle part having a ward thereon, a central part and an end part, the latter parts each having a wing thereon, an extension on the end part entering the central part for rotatably connecting the parts together, said parts having notches in their abutting ends, a number of members carried by the end part for engaging the notches for locking the two parts together when their wings are turned at right angles to each other, spring means for projecting the members and the central part having a keyhole for receiving the ward which forces the members out of the slots in the central part.
2. A key, comprising a handle part having a ward thereon, a central part and an end part, the latter parts each having a wing thereon, an extension on the end part entering the central part for rotatably connecting

the parts together, said parts having notches in their abutting ends, a number of members carried by the end part for engaging the notches for locking the two parts together when their wings are turned at right angles to each other, spring means for projecting the members and the central part having a keyhole for receiving the ward which forces the members out of the slots in the central part and means for preventing withdrawal of the ward when the parts are in unlocking position.

3. A key of the class described, comprising a handle part having a ward thereon, a central part having a wing thereon provided with an extension to enter a part of the keyhole of the lock, said central part having a keyhole for receiving the ward, the parts being formed to prevent withdrawal of the ward when the handle part is turned, an end part having a wing thereon for engaging the keyhole of the lock and a shoulder for limiting the movement of the part in the lock, said central part and end part having notches in their abutting ends, winged members in said parts with the wings engaging the notches, a spring for projecting the wing members and said members having their ends shaped to engage different portions of the ward so that said members will be moved by the ward at different times.

In testimony whereof I affix my signature.
ROBERT TOENNIGES.
